UNITED STATES PATENT OFFICE

147,899

DESIGN FOR A CONDIMENT SHAKER

Rolf John Falk, Zanesville, Ohio, assignor to Shawnee Pottery Company, Zanesville, Ohio, a corporation of Ohio

Application April 20, 1946, Serial No. 128,806

Term of patent 14 years

(Cl. D44—22)

To all whom it may concern:

Be it known that I, Rolf J. Falk, a citizen of the United States of America, residing at Zanesville, in the county of Muskingum and State of Ohio, have invented a new, original, and ornamental Design for Condiment Shaker, of which the following is a specification, reference being had to the accompanying drawings, forming a part thereof, wherein:

Fig. 1 is a side elevation of a condiment shaker illustrating my new design;

Fig. 2 is a front elevation thereof; and

Fig. 3 is a rear elevation thereof.

I claim:

The ornamental design for a condiment shaker, as shown.

ROLF JOHN FALK.
